Attorney.

UNITED STATES PATENT OFFICE.

HACHIG A AYVAD, OF EMPORIA, VIRGINIA.

FLYING-MACHINE.

1,369,875.

Specification of Letters Patent. Patented Mar. 1, 1921.

Application filed August 25, 1917. Serial No. 188,099.

To all whom it may concern:

Be it known that I, HACHIG A AYVAD, a citizen of the United States of America, and a resident of Emporia, in the county of 5 Greensville and State of Virginia, have invented certain new and useful Improvements in Flying-Machines, of which the following is a specification.

This invention has for an object the provision of a flying-machine which cannot be overturned in passing through rising or falling air-currents which are not the same on the two sides. A further object is to provide a flying-machine in which there are 10 reserve planes to be brought into service in event of any of the other planes being broken off, as for example, by being shot away in battle, and to provide for the bringing of such reserve planes automatically into 15 service position and without attention from the pilot. A further object is to provide a means for steering the flying-machine by adjusting the angles, horizontal and vertical between the planes on the one hand and the 20 car and propeller-axis on the other. A further object is to provide a form of plane 25 which is reversible and which will automatically under the pressure of the air bend to the most efficient form whichever side is presented to the air pressure.

In the accompanying sheet of drawings which forms a part of this application,

Figure 1 is a side elevation of a flying-machine in flight embodying this invention, 35 the car being shown in section on the line I—I of Fig. 2;

Fig. 2 is a front elevation of the same; and

Fig. 3 is a top or plan view.

The flying-machine depends for its support on a series of wings or planes each having a partially bounding frame 4 within which a flexible sheet 5 is stretched. These wings are equally spaced around an axle 6, 45 and when not stressed the wings lie in a series of radially disposed planes having the axis of the axle in common. The wings taken together constitute a multiplane and when there are eight wings, which is considered to be the preferable number, it may be 50 termed an "octoplane." When set so that two of the wings are vertical, these two serve as rudders, and the other six are effective supporting planes, two being horizontal and 55 four setting at angles of forty-five degrees

to the horizontal. Peripheral lines of bracing 7, 7, which may be of cords or stiff rods, are carried around the wings of the multiplane at the forward edges and at the outer edges but not at the rear edges and are attached to the ribs of each wing in any suitable manner, as by knotting at eyes 8, 8. The sheets of the supporting wings will bag with the pressure of the air on their under sides and assume a concave form. This bagging taken in connection with a certain flexibility of that part of the bounding frame which is not braced will allow the concavity to flatten out at the rear and so bring each supporting wing as a whole to a curvature 70 which is greatest near the forward edge and concave underneath and convex above no matter which side up the wing is used. This multiplane is mounted in bearings 9, 9 at the upper ends of a yoke 10 and is revolute 75 in these bearings. The bearings are purposely large so as to introduce a certain amount of friction and steady the multiplane against revolving except when the wings on the two sides encounter materially 80 different rising or falling air currents and will stop the revolution as soon as such currents are passed by. When the multiplane runs into air currents which are different on the two sides, sufficient revolution takes 85 place to equalize the difference so as to prevent the overturning of the flying-machine. Also, if one or more of the wings should be broken off or otherwise be put out of condition, the multiplane will turn so that such 90 wings as are left will take a symmetrical position if possible on the two sides of the vertical so as to afford support.

A car 11 is suspended from the yoke through a post 12 to which the yoke is pivoted. A second post 13 has a slot in its side which guides the forward edge of the yoke. The yoke may be tilted by turning a wheel and screw 14 and the multiplane thereby tilted upward or downward. The two posts 100 rise from a bar 15 which is connected through a vertical pin 16 and a horizontal curved guide 17 with the frame of the car, thereby forming a structure which may be likened to the fifth wheel of a wagon but inverted. Its purpose is to permit of horizontal adjustment between the multiplane some of the planes of which act as rudders on the one hand and the car and propeller on the other hand for the purpose of steering.

The car carries an engine 18 and a propeller 19. The propeller is carried by a shaft 20 mounted in bearings 21, 21 supported from the car and above the car so that the line of propulsion will lie between the car and the multiplane. The transmission from the engine shaft 22 is through a pulley 23, rope belt 24, and pulley 25.

In flying, the flying-machine is directed 10 up or down by turning the wheel to adjust the amount of tilt of the multiplane as needed. Steering horizontally is effected by moving the multiplane to the right or left, this being effected by pushing the wheel bodily over to one side or the other. The pilot 15 can therefore with his hands without relaxing hold of the wheel exercise control of both vertical and horizontal direction. The wings are narrower at the rear to prevent

the flying-machine in alighting from plunging headlong.

What I claim as new, and desire to secure by Letters Patent of the United States, is—

A revoluble multiplane consisting of a series of radially disposed wings, the plane 25 of each wing lying substantially in the axis of the multiplane, each wing consisting of a flexible sheet stretched in a frame, the frame being braced at the forward edge and permitted to flex at its rear edge whereby the 30 sheet will become concave toward the direction of air pressure with the concavity flattened toward the rear, substantially as described.

Signed at New York, N. Y., this 23rd day 35 of August, 1917.

HACHIG A AYVAD.
